UNITED STATES PATENT OFFICE.

BESSIE M. BLATNER, OF CHICAGO, ILLINOIS.

NOVELTY PLACE CARD.

Application filed January 17, 1924. Serial No. 686,713.

To all whom it may concern:

Be it known that I, BESSIE M. BLATNER, a citizen of the United States, residing at Chicago, in the county of Cook and State of Illinois, have invented certain new and useful Improvements in Novelty Place Cards, of which the following is a specification.

The card of this invention is designed not only to afford an attractive place card for luncheon or dinner service, but is also designed to serve as a candle holder without the necessity for providing a separately formed candle socket, thereby reducing the cost of manufacture to a minimum, enabling the cards to be readily packed in flatwise relation and avoiding the liability of loss or displacement of attachments designed for candle holding purposes.

In the drawing:

20 Figure 1 is a perspective view of the card in use with a candle inserted; and

Fig. 2 is a plan view of the card without the candle.

The card A is of rectangular form and 25 of the customary size for dinner cards, and it may be decorated or embellished in any suitable manner. The card is provided, preferably near one end thereof, with two intersecting cuts B which afford four inwardly 30 converging tongues C which may be bent upwardly as indicated to provide for the support of a candle D.

The candle may be easily inserted from beneath by forcing up the tongues, after 35 which the candle is moved to a position to bring its butt end flush with the bottom of the card and with the tongues in upwardly

protruding position around the base of the candle. The pointed form of the upper portion of the candle facilitates the insertion 40 thereof and the flexibility of the card permits the tongues to be sprung upwardly as indicated, and after insertion the tongues will press firmly against the surface of the candle by reason of the spring action of the 45 card, so that the candle will be firmly held in upright position. At the same time, the major portion of the card surface will remain unobstructed for the filling in of the name, so that the device will not only serve 50 as an attractive place card, but also as a source of illumination.

I claim:

1. A plane flat novelty card provided with cuts furnishing converging tongues, and a 55 candle entered between said tongues and serving to spring said tongues into elevated relation and into position to bring the tongues into firm engagement with the side wall of the candle near its base, substantially 60 as described.

2. A plane flat novelty card provided with intersecting cuts furnishing tongues having their apices in converging relation, and a candle entered between said tongues 65 and serving to spring said tongues into elevated relation and into position to bring the apices of the tongues into firm contact with the side wall of the candle above the butt end thereof, said butt end lying flush with 70 the underside of the card, substantially as described.

BESSIE M. BLATNER.
